OPTICAL DENSITY MEASURING INSTRUMENT

Victor Italiano, 213 Leroy St., Binghamton, N.Y.

Filed May 23, 1962, Ser. No. 70,249

Term of patent 14 years

(Cl. D57—1)

FIG. 1

FIG. 4

FIG. 2

FIG. 3

FIG. 1 is front perspective view of an optical density measuring instrument, showing my new design.

FIG. 2 is a front elevational view thereof;

FIG. 3 is a back elevational view thereof; and

FIG. 4 is a rear perspective view thereof.

I claim:

The ornamental design for an optical density measuring instrument, substantially as shown.
